UNITED STATES PATENT OFFICE.

MARC GRANDJEAN, OF PARIS, FRANCE, ASSIGNOR TO SOCIETE ANONYME STENOTYPE
GRANDJEAN, OF PARIS, FRANCE.

STENOGRAPHIC MACHINE.

Application filed February 18, 1927, Serial No. 169,380, and in France March 16, 1926.

The present invention has for its object improvements in stenographic machines with a view of simplifying the construction and the assembling, and of simultaneously regulating the force of the stroke in all the keys, and of deadening the noise which they produce.

For this purpose, all of the key levers are pivoted, at the end opposite the one carrying the key, to an axle which passes through an assembled set of thin blades properly spaced apart and forming in pairs suitable recesses in which these ends of the levers are guided in a regular manner.

The aggregate of the said guiding plates forms a device which may be readily and economically constructed and which offers a great precision. The guiding device is advantageous in many respects as compared with the comb-shaped elements which have hitherto been employed to guide the key levers.

The said key levers are returned to the inoperative position by springs which are mounted on a common pivoting element which is provided with an abutment for the levers; said abutment, which limits the upward stroke of the levers, consists of a cylinder of wood or other non-metallic substance which is covered with a suitably striated rubber sheath.

The appended drawings show by way of example an embodiment of the invention as applied to a keyboard for training purposes.

Fig. 1 is a side elevation of the keyboard, with certain parts in section.

Fig. 2 is a plan view, with parts broken away.

Fig. 3 is a cross section on the line 3—3 of Fig. 2.

The said training keyboard comprises, like the regular keyboard, 21 keys 1 mounted upon the levers 2 which are disposed fanwise and are pivoted to an axle 3 extending through a suitable guiding device which is disposed at the rear of the keyboard.

The said device comprises two angle brackets 4 which are held by four screwthreaded rods 5 and 5^a, 6 and 6^a and by nuts, and also two sets of spacing pieces between which are disposed the strips or blades 9 which may consist of hoop iron and form partitions. The spacing pieces 7 and 8 have a thickness which very slightly exceeds that of the levers 2, so as to maintain suitable spaces be-

tween the strips 9 for the accurate guiding of the levers upon the whole length upon which they are engaged in the guiding device.

The screw threaded rods 5 and 5^a, with their nuts, serve to secure to the guiding device a strap 10, consisting for example of pressed wrought iron, which can be pivotally mounted on the rod 5 since it is pierced with the slots 11 for the insertion of the rod 5^a.

The strap 10 is braced at the front part, on the side next the keyboard, by a cast iron cross-piece 12 pierced with apertures for the insertion of the springs 13 which are engaged in the recesses formed between the strips 9 and which bear upon the key levers in such manner as to hold them in the raised position. The outer ends of the springs are bent at right angles and are disposed in a set of parallel grooves which are formed by the casting process, together with the cross-piece 12; these ends are held in the grooves by the bar 12^a which is screwed to the cross-piece 12. This method of assembling by screws is advantageous from the fact that a single spring may be replaced without interfering with the others.

The outer ends of the latter are connected together by a sheet metal cylinder 14 which is covered by a rubber sheath whose surface is striated. The cylinder 14 when thus covered will form an abutment for the levers when raised. By removing the nuts at the ends of the rods 5—5^a, I may turn the member 10 and the members disposed thereon, so as to adjust in the first place the pressure of the springs 13 upon the levers and hence the force of the stroke, and then the stroke of the said levers, and these two operations can be carried out at the same time.

The lower abutment for the levers consists of an axle 16 of steel or the like which is covered by a sheath of smooth rubber 17; the said abutment is disposed on a member 18 analogous to the member 10, and is pivotally mounted on the rod 6^a, it being provided for this purpose with slots 19 by which it is engaged upon the rod 6, and I can thus easily regulate the stroke of the levers in the downward direction when the keys are pressed.

The keyboard thus formed is contained in a case 20 and is secured thereto by a plate 21 mounted on the angle brackets 4.

The said keyboard possesses numerous advantages over those in current use upon steno-

graphic machines. Due to the guiding device for the levers as thus constructed, I dispense with the combs—usually four in number—which are employed in the machines to 5 guide the levers at the top and bottom, and at several points upon their length, this arrangement being difficult to assemble and adjust. With the use of such combs as guides, the combs must be adjusted tooth by tooth to 10 provide for the free motion of the levers without friction, but in my said guiding device no such adjustment is necessary, and the pieces may be manufactured in standard types.

15 The force of the stroke is adjusted at the same time for all the levers, due to the mounting of all the springs upon the cross-piece 12 of the member 10; the springs are all made of the proper length, and consist for instance 20 of piano wire, and if they are given the proper shape by means of a special tool outfit, the proper force of the stroke in a given keyboard can be obtained in a single operation by raising or lowering the cross-piece 12.

25 By employing for the upper abutment for the levers, a wood or like cylinder 14 covered with a rubber sheath 15, I am enabled to obviate all noise, inasmuch as the ascending lever will meet only with a relatively elastic 30 portion, and since the vibration passes through various non-metallic substances, it will be reduced and not increased. For this reason, the noise is wholly or partially eliminated.

35 As above stated, the upward and downward stroke of the levers is regulated in a very simple manner by the pivoting of the respective members 10 and 18 in either direction.

Obviously, the said invention is not limited 40 to the form of construction above specified by way of example, and it is susceptible of all modifications in the form, disposition and assembling of the several parts.

45 For example, the lower abutment for the levers may have the same construction as the upper abutment.

50 It is evident that the said improvements are applicable to keyboards for actual stenographic machines as well as to those of training machines, it being understood that the key levers will be properly connected with the type levers, and that the other parts of the machine such as the striking roller, the winding device and the like will be properly disposed.

55 In the case of a stenographic machine, the lower abutment for the levers will become useless, and it may be dispensed with, since the downward stroke of the levers is limited 60 by the contact between the type pieces and the striking cylinder, and by the limited play of the pivots of the key levers and the type levers.

Having thus described my apparatus,

what I claim as new therein, and my own 65 invention, is:—

1. In a stenographic machine, the combination of key-levers, an axle about which pivot the said key-levers, rigid flat blades disposed between the said key-levers and 70 traversed by said axle, spacing members between the said blades, the width of the said spacing members being slightly larger than that of the levers and means for assembling together into a block the said blades and the 75 said spacing members, the said blades being adapted to guide between them the said levers.

2. In a stenographic machine, the combination of key levers, axles having the said 80 levers pivotally mounted thereon, means for guiding the said levers in the vicinity of the said axles, said means comprising strips forming long walls between which the said key levers are engaged, and spacing members between said strips for properly spacing the latter, the spacing of the said strips 85 slightly exceeding the spacing of the said levers, two angle brackets between which are disposed in a single device the said strips and spacing members, and screwthreaded rods extending through the said strips and spacing members whereby the latter will be suitably maintained in the assembled position.

3. In a stenographic machine, the combination of key levers, axles having the said 90 levers pivotally mounted thereon, means for guiding the said levers in the vicinity of the said axles, said means comprising strips forming long walls between which the said key levers are engaged, and spacing members between the said strips for properly 95

spacing the latter, the spacing of the said strips slightly exceeding the spacing of the 100 said levers, two angle brackets between which 105 are disposed in a single device the said strips and spacing members, screwthreaded rods extending through the said strips and spacing members whereby the latter will be suitably maintained in the assembled position, 110 two members pivoting on either side of the said levers, and an abutment provided on each of the said members and serving to limit the stroke of said levers in the upward and 115 downward directions.

4. In a stenographic machine, the combination of key levers, axles having the said 120 levers pivotally mounted thereon, means for guiding the said levers in the vicinity of the said axles, said means comprising strips forming long walls between which the said key levers are engaged, and spacing members between the said strips for properly spacing the latter, the spacing of the said strips slightly exceeding the spacing of the said levers, 125 two angle brackets between which are disposed in a single device the said strips and spacing members, screwthreaded rods ex-

tending through the said strips and spacing members whereby the latter will be suitably maintained in the assembled position, two members pivoting on either side of the said levers, an abutment provided on each side of the said members and serving to limit the stroke of the said levers in the upward and downward directions, said abutment consisting of a wood support and a sheath of suitable material for deadening the sound which is mounted on the said support.

5. In a stenographic machine, the combination of key levers, axles having the said levers pivotally mounted thereon, means for guiding the said levers in the vicinity of the said axles, said means comprising strips forming long walls between which the said key levers are engaged, and spacing members between the said strips for properly spacing the latter, the spacing of the said strips slightly exceeding the spacing of the said levers, two angle brackets between which are disposed in a single device the said strips and spacing members, screwthreaded rods extending through the said strips and spacing members whereby the latter will be suitably maintained in the assembled position, two members pivoting on either side of the said levers, an abutment provided on each of the said members and serving to limit the stroke of said levers in the upward and downward directions, reaction springs controlling the said levers, the member supporting the said upward abutment having a bar adapted to carry all the springs of the said levers, the said bar being provided with apertures, and the ends of said springs being inserted in said apertures, grooves formed in the said bar, the ends of said springs being bent at right angles and engaged in the said grooves, the other ends of the said springs being in contact with the said levers, and a bar which is mounted on the said member and serves to maintain in the said grooves the front ends of said springs.

6. In a stenographic machine, the combination of keys levers, axles having the said levers pivotally mounted thereon, means for guiding the said levers in the vicinity of the said axles, said means comprising strips forming long walls between which the said key levers are engaged, and spacing members between the said strips for properly spacing the latter, the spacing of the said strips slightly exceeding the spacing of the said levers, two angle brackets between which are disposed in a single device the said strips and spacing members, screwthreaded rods extending through the said strips and spacing members whereby the latter will be suitably maintained in the assembled position, two members pivoting on either side of the said levers, an abutment provided on each of the said members and serving to limit the stroke of said levers in the upward and downward directions, reaction springs controlling the said levers, the member supporting the said upward abutment being adapted to carry all the springs of the said levers, the said member being apertured at the ends, and the ends of said springs being adapted for insertion through the apertures, grooves formed in the said member, the ends of said springs being bent at right angles and engaged in the said grooves, the other ends of the said

springs being in contact with the said levers.

7. In a stenographic machine, the combination of key levers, axles having the said levers pivotally mounted thereon, means for guiding the said levers in the vicinity of the said axles, said means comprising strips forming long walls between which the said key levers are engaged, and spacing members between the said strips for properly spacing the latter, the spacing of the said strips slightly exceeding the spacing of the said levers, two angle brackets between which are disposed in a single device the said strips and spacing members, screwthreaded rods extending through the said strips and spacing members whereby the latter will be suitably maintained in the assembled position, two members pivoting on either side of the said levers, an abutment provided on each of the said members and serving to limit the stroke of said levers in the upward and downward directions, reaction springs controlling the said levers, the member supporting the said upward abutment having a bar adapted to carry all the springs of the said levers, the said bar being provided with apertures, and the ends of said springs being inserted in said apertures, grooves formed in the said bar, the ends of said springs being bent at right angles and engaged in the said grooves, the other ends of the said springs being in contact with the said levers, and a bar which is mounted on the said member and serves to maintain in the said grooves the front ends of said springs.

8. In a stenographic machine, the combination of key levers, axles having the said levers pivotally mounted thereon, means for guiding the said levers in the vicinity of the said axles, said means comprising strips forming long walls between which the said key levers are engaged, and spacing members between the said strips for properly spacing the latter, the spacing of the said strips slightly exceeding the spacing of the said levers, two angle brackets between which are disposed in a single device the said strips and spacing members, screwthreaded rods extending through the said strips and spacing members whereby the latter will be suitably maintained in the assembled position, two members pivoting on either side of the said levers, an abutment provided on each of the said members and serving to limit the stroke of said levers in the upward and downward directions, reaction springs controlling the said levers, the member supporting the said upward abutment being adapted to carry all the springs of the said levers, the point of action of said springs upon the said levers being as close as possible to the said pivoting axle.

In testimony whereof I have hereunto affixed my signature.

MARC GRANDJEAN.
